DESIGN FOR A PIECE OF BRIC-A-BRAC

Clarence William Parker, Lynn, Mass.

Application March 14, 1941, Serial No. 99,597

Term of patent 14 years

To all whom it may concern:

Be it known that I, Clarence W. Parker, a citizen of the United States, residing at Lynn, in the county of Essex and State of Massachusetts, have invented a new, original, and ornamental Design for a Piece of Bric-A-Brac, of which the following is a specification, reference being had to the accompanying drawing, forming part thereof.

The single view is a perspective of a piece of bric-a-brac showing my new design.

I claim:

The ornamental design for a piece of bric-a-brac, as shown.

CLARENCE WILLIAM PARKER.
